TELEPHONE SYSTEM HAVING A CALLING
AND SUPERVISORY SIGNALING DEVICE

Don H. Young, Valley Stream, and Frank R. Mallalieu, Forest Hills, N. Y., assignors to Dictograph Products Company, Inc., New York, N. Y., a corporation of Delaware

Application April 3, 1946, Serial No. 659,230

8 Claims. (Cl. 179—75)

1

This invention relates to improvements in telephone systems, and it relates particularly to improvements in local battery telephone systems and switchboard circuits of the type disclosed in the Don H. Young application Serial No. 534,202, filed May 5, 1944, now Patent No. 2,393,354, dated January 22, 1946.

An object of the invention is to provide simplified local battery telephone systems having combined calling and supervisory signalling means.

Another object of the invention is to provide local battery telephone systems in which a single signalling means serves both as a call signal and a supervisory signal.

A further object of the invention is to provide telephone systems including signalling means of the electronic tube type that are responsive to call signals properly transmitted along the telephone lines and not responsive to stray radio frequency signals picked up by the lines or interpair line leakages.

Other objects of the invention will become apparent from the following description of typical forms of telephone systems embodying the present invention.

In accordance with the present invention, we have provided a local battery telephone system in which an electronic glow tube is used, at the switchboard, for signalling a call from a party, the tube being arranged also to indicate the end of the telephone call.

More particularly, the switchboards of the type embodying the present invention are provided with a plurality of electronic glow tubes, preferably having four elements including the cathode, two grids and a plate. One tube is provided for each station and is directly responsive to calls from that station.

The switchboard is provided with suitable switching mechanism by means of which the operator's telephone set can be connected with the line of the party making the call and the line of the called party and transmit a suitable signal to the called party.

Each signalling tube is normally in a condition to be set into operation by a signal from the party making the call, except when the operator at the switchboard cuts in to answer the call or to supervise the call.

The telephone sets in the party stations are arranged to provide a signal for energizing the signalling tubes at the beginning and at the end of the call so that the tube is energized and caused to glow at the beginning and at the end of the call, thereby keeping the operator advised as to the use of the telephone lines.

2

Such systems may be provided with suitable filter circuits whereby the undesired energization of the signal tubes by radio frequency signals picked up by the lines, and interpair leakage of the lines can be avoided.

For a better understanding of the present invention reference may be had to the accompanying drawings in which:

Figure 1 is a schematic wiring diagram of a typical system embodying the present invention; and

Figures 2, 3, 4 and 5 are schematic diagrams of suitable filter circuits to be used in the telephone system shown in Figure 1.

15 Telephone systems of the type embodying the present invention and illustrated in Figure 1 of the drawings are useful for communications operations in the Armed Forces and in rural localities, inasmuch as they will operate satisfactorily under conditions that would completely disrupt service with the more sensitive and modern common battery systems. Thus, for example, when the lines are temporarily short-circuited between stations, the signalling tubes will not be caused to glow and even when there are substantial variations in the resistance of the wires or lines, effective signalling and message transmission is still possible.

The form of the invention disclosed in Figure 30 1 is a modification of the system disclosed in the Young application Serial No. 534,202 and the telephones provided in the party stations may be identical with those disclosed in that application. For example, the local telephone circuit for a party "A" may include a transmitter 10 and a receiver 11 which may be mounted in the usual wall, desk, or hand set type of casing. A switch 12 is interposed between the line 13 and the receiver 11 which is responsive to removal of the receiver or the handset from the hook or cradle. The opposite side of the receiver 11 is connected by means of a conductor 14 and the secondary winding 15 of a transformer 16 to the line 17. The transmitter 10 is connected by means of the conductor 14 and another hook switch 18 to one pole of a battery 19, through the other pole of the battery 19 to the primary winding 20 of the transformer 16 and to the other side of the transmitter 10, thereby constituting a talking circuit when the hook switch 18 is closed. One pole of the battery 19 is also connected by means of a conductor to the primary winding 21 of a step-up transformer 22. The opposite end of the winding 21 is connected to one contact of a pulsating switch 23 which is connected to the opposite pole of the battery 19. An audible sig-

nalling member 24 is also connected between the telephone lines 13 and 17 to indicate incoming calls in the conventional manner.

The pulsating switch is so arranged that when the receiver is lifted from the cradle or hook, the contacts are set into vibration in order to produce a pulsating current that can be stepped up in the transformer 22 and transmitted to the central board in order to indicate at the switchboard an incoming call. Likewise, when the receiver or hand set is returned to the hook or cradle, the pulsating switch 23 is set into operation to transmit a signal to the main switch board to indicate the end of the conversation or call.

The lines 13 and 17 terminate at the switch board in the contacts 26a and 26b respectively of the plug 26. This plug normally is adapted to be received in a jack 27 having the contacts 27a and 27b for engaging the plug contacts 26a and 26b respectively. The jack contacts 27a and 27b are connected through the limiting resistors 28 and 29 to the grids 30a and 30b respectively of a four-element glow tube 30. The glow tube 30 is provided with a plate 30c and a cathode 30d, the latter being connected to the conductor 31 which is in turn connected to one pole of a local battery or other source of power 32.

The plate 30c is connected by means of a conductor 33 to a switch contact 34a which normally engages a fixed contact 34c that is connected to the conductor 35 which is connected to the opposite pole of the local battery 32. The electronic tube circuit described above is such that normally a potential is applied to the plate 30c and the cathode 30d, this potential, however, being insufficient to cause a discharge between the plate and cathode which would energize the tube and cause it to glow. When, however, a ringing signal is received, for example, from along the lines 13 and 17 as a result of lifting the receiver from the hook, the signalling potential is applied to the grids 30a and 30b, thereby causing the gas in the tube to ionize, allowing current to flow between the plate 30c and the cathode 30d and causing the tube to glow, indicating an incoming call. If desired, a relay 36 may be connected in the circuit between the battery 32 and the glow tube 30, so that an audible signal may be produced by the discharge or flow of current through the tube. The relay 36 may be connected, as illustrated, in the conductor 35.

In order for the operator at the switchboard to talk to the party, a switch is provided whereby the operator's bus wires 37 and 38 may be connected to the lines 13 and 17. As shown, the bus wire 37 is connected to a fixed contact 39a of a switch 39 and to a fixed contact 34d of the switch 34. The contact 39a cooperates with a normally open switch contact 39b which is connected to the line 17. The contact 34d cooperates with a normally open contact 34e also connected to the line 17.

The operator's talking circuit also includes a conductor 40 which connects the bus wire 38 to a fixed contact 41a of a switch 41 and to the fixed contact 42a of the switch 42. The fixed contact 41a cooperates with a normally open contact 41b of the switch 41, which is connected to one contact 43a of a jack 43 and to the movable contact 42b of the switch 42.

The contact 43b of the jack 43 is connected to the line 17.

The fixed contact 41c of the switch 41 is connected to the line 13.

The movable contacts 34a and 34e and 42b

move simultaneously when the operator's switch is moved in the direction indicated by the arrow identified as "Talk," thereby disengaging the contacts 34a and 34c and engaging the contacts 34d and 34e and also engaging the contacts 42a and 42b. With the contacts in this latter position, the circuit between the battery 32 and the tube 30 is open, with the result that the tube 30 is extinguished. At the same time, the operator's bus wire 37 is connected through the contacts 34e and 34d to the line 17 and the bus 38 is connected through the contacts 42a, 42b, 41b and 41c to the line 13 so that the operator can converse with the party calling.

The switchboard described above is provided with as many telephone circuits like that described above as there are parties in the system. A second signal system corresponding to another party "B" is illustrative of a plurality of such additional stations. The system corresponding to the party "B" is provided with a plug 45, a jack 46 for receiving it, a glow tube signalling mechanism 47, and the ringing and talking switches 48 and 49 and a jack 50 similar to the jack 43. When the party "A" of the first described system desires to talk with the party "B," the operator will withdraw the plug 45 from the jack 46 and insert it in the jack 43 of the "A" system. This connects the lines 51 and 52 of the system "B" with the lines 13 and 17 respectively so that a conversation can be carried on between the party at station "A" and the party at station "B."

In order to call the attention of the party at station "B" to the call, the operator at the switchboard will actuate the control switch in the direction of the arrow marked "Ring," thereby disengaging the contacts 41b and 41c and engaging the contacts 41a and 41b and at the same time engaging the contacts 39a and 39b. This operation disconnects the party "A" from the operator's bus wires 37 and 38. In the meantime, by moving the switch to central position or past the direction of "Ring," the switches 34 and 42 will be restored to the positions shown in the drawing. When the ringing circuit is closed, the operator by applying a suitable high alternating potential to the bus wires 37 and 38 will operate the signalling means at the station of the party "B" through the conductor 40, the contact 41a, the contact 41b and the jack contact 43a and through the switch contacts 39a and 39b and the jack contact 43b. When the ringing signal has been given, the operator's switch may be restored to neutral position and the conversation may be carried on by the party "A" and the party "B" through the connections described above.

At this time, the glow tube 30 will also be reconditioned for further energization, inasmuch as the potential from the battery 32 is again applied to the cathode 30c and the cathode 30d.

The operator may cut in at any time to determine whether the lines are still in service by merely moving the switch to the "Talk" position.

At the conclusion of the conversation, when the party at station "A" restores his receiver or hand set to the hook or cradle, a signal voltage of sufficient magnitude is transmitted from the vibratory switch 23 to the glow tube 30 to energize the grids 30a and 30b and cause the tube 30 to glow. The signal provided by the tube 30 advises the operator that the conversation is concluded and the operator may then withdraw the plug 45 from the jack 43 and reinsert it in the jack 46 to restore the switchboard to a condi-

tion whereby it may be used by the party "B" for calling other parties connected to the system.

Systems of the type described above are somewhat sensitive to radio frequency signals picked up by the telephone lines, particularly when the lines pass near a powerful radio transmitter. Also, false operation of the signalling tubes 30 or 47 may occur because of leakage between the pairs of telephone lines.

This can be overcome to a certain extent by means of the limiting resistors 28 and 29 in each of the circuits. These resistors may have a value in the range of 25,000 to 2 megohms and act to limit the current to the rated current of the particular tube used. This circuit gives some false signals in practice.

As shown in Figure 2, the false signals caused by pickup of radio frequency voltages may be eliminated by introducing a pair of condensers 55 and 56 between the limiting resistors 28a and 29a and connecting one terminal of the battery 32' to a midpoint between the condensers 55 and 56. Elements of the tube and circuit connections corresponding to parts disclosed in Figure 1 are identified in Figure 2 by primed reference characters.

False signals due to interpair leakage in the lines may be overcome by connecting loading resistor 57 across the lines leading to the limiting resistors 58 and 59 which are connected to the grids of the tube as shown in Figure 3. Inasmuch as the grids of the tube normally present a very high impedance to the line, spurious voltages frequently may be reduced so that they will not be troublesome merely by providing a loading resistor 57 having a value between 5,000 and 50,000 ohms across the input.

A somewhat different arrangement is disclosed in Figure 4 which, in addition to loading the line, tends to balance it to the tube to ground and maintains the tube grids at switchboard ground potentials. In this form, two resistors 60 and 61 are connected across the line and the midpoint is connected to the battery 32" through a third resistor 62. The sum of the values of the resistances 60 and 61 preferably should be somewhat less than that of the limiting resistors 63a and 63b. If desired, the resistors 60 and 61 may be connected across the grids instead of across the lines.

The form disclosed in Figure 5 is the preferred form, inasmuch as it stabilizes the system against both interpair leakage and radio frequency voltages. In this form, a pair of resistances 64 and 65 are connected across the line and a pair of condensers 66 and 67 are connected across the grids of the tube 30". The midpoint between the resistances 64 and 65 and the condensers 66 and 67 are connected to ground or to the battery 32''' with a resistor 68 connected between the midpoints referred to above. By the use of this latter circuit, radio frequency signals are filtered out and the resistance of the circuit is such that interpair leakage potentials have no effect upon the energization of the tube.

From the preceding description, it will be apparent that we have provided a simplified form of local battery telephone system in which fewer tubes are required for providing call and supervisory signals and in which the system is rendered insensitive to radio frequency voltages induced in the lines and leakage between the pairs of lines.

It will be understood that there may be some variations in the arrangement of the operator's

switching mechanism and that other means than vibrating switches may be used for igniting the glow tube. Therefore, the form of the invention described above should be considered as illustrative and not as limiting the scope of the following claims.

We claim:

1. In a local battery telephone system, the combination of at least two, two-wire telephone lines, telephone sets connected to said lines, a switchboard, a glow tube at the switchboard corresponding to each of said telephone lines, each tube having a cathode, a plate and a pair of grids, a switchboard operator's telephone set at said switchboard, means connecting the wires of each telephone line to different grids of its corresponding glow tube, means for applying a potential to said cathode and plate of each tube insufficient to cause said tubes to glow but sufficient to maintain said tubes glowing upon energization of said grids, means at the telephone set connected to each line for applying a potential to said lines sufficient to energize said grids of the corresponding tube and cause said tube to glow, and a switching means for connecting said operator's telephone set to a telephone line and simultaneously removing the potential from the plate and cathode of the tube corresponding to the line to which the operator's set is connected.
2. In a local battery telephone system, the combination of at least two, two-wire telephone lines, a telephone connected to each of said lines, a switchboard, electronic glow tubes at the switchboard corresponding to each telephone line, each tube having a plate, a cathode and two grids, jacks having a pair of contacts each connected to different grids of a tube, a plug fitting said jack having separate contacts connected to the wires of a line and receivable in the jack of the corresponding tube to connect said lines to the grids of its corresponding tube, means for applying a potential to the plates and cathodes of said tubes of a magnitude insufficient to cause said tubes to glow but sufficient to maintain said tubes glowing after energization of said grids, means at each of said telephone sets for energizing the grids of its corresponding tube to cause said corresponding tube to glow, other jacks corresponding to each line at said switchboard, normally engaged switching means connecting each jack to its corresponding telephone line, each of said other jacks being adapted to receive the plug of the line not corresponding to the other jack to interconnect said lines, said switching means being operable to disconnect said other jack from its corresponding line.
3. In a local battery telephone system, the combination of at least two, two-wire telephone lines, a telephone connected to each of said lines, a switchboard, electronic glow tubes at the switchboard corresponding to each telephone line, each tube having a plate, a cathode and two grids, jacks having a pair of contacts each connected to different grids of a tube, a plug fitting said jack having separate contacts connected to the wires of a line and receivable in the jack of the corresponding tube to connect said lines to the grids of its corresponding tube, means for applying a potential to the plates and cathodes of said tubes of a magnitude insufficient to cause said tubes to glow but sufficient to maintain said tubes glowing after energization of said grids, means at each of said telephone sets for energizing the grids of its corresponding tube to cause said corresponding tube to glow, other jacks cor-

responding to each line at said switchboard, normally engaged switching means connecting each jack to its corresponding telephone line, each of said other jacks being adapted to receive the plug of the line not corresponding to the other jack to interconnect said lines, said switching means being operable to disconnect said other jack from its corresponding line, and means at the switchboard for applying a ringing potential to said other jack when the latter is disconnected from its corresponding line.

4. In a local battery telephone system, the combination of at least two, two wire telephone lines, telephone sets connected to said lines, a switchboard, a glow tube at the switchboard corresponding to each of said telephone lines, each tube having a cathode, a plate and a pair of grids, a switchboard operator's telephone set at said switchboard, means connecting the wires of each telephone line to different grids of its corresponding glow tube, means for applying a potential to said cathode and plate of each tube insufficient to cause said tubes to glow but sufficient to maintain said tubes glowing upon energization of said grids, means at each telephone set connected to a telephone line for applying a potential to said line sufficient to energize the grids of the corresponding tube and cause said tube to glow, means interposed between each line and its corresponding tube for filtering out potentials due to interpair line leakages.

5. In a local battery telephone system, the combination of at least two, two wire telephone lines, telephone sets connected to said lines, a switchboard, a glow tube at the switchboard corresponding to each of said telephone lines, each tube having a cathode, a plate and a pair of grids, a switchboard operator's telephone set at said switchboard, means connecting the wires of each telephone line to different grids of its corresponding glow tube, means for applying a potential to said cathode and plate of each tube insufficient to cause said tubes to glow but sufficient to maintain said tubes glowing upon energization of said grids, means at each telephone set connected to a telephone line for applying a potential to said line sufficient to energize the grids of the corresponding tube and cause said tube to glow, means interposed between each line and its corresponding tube for filtering out potentials due to pickup of radio frequency signals by said lines.

6. In a local battery telephone system, the combination of at least two, two wire telephone lines, telephone sets connected to said lines, a switchboard, a glow tube at the switchboard corresponding to each of said telephone lines, each tube having a cathode, a plate and a pair of grids, a switchboard operator's telephone set at said switchboard, means connecting the wires of each telephone line to different grids of its corresponding glow tube, means for applying a potential to said cathode and plate of each tube insufficient to cause said tubes to glow but sufficient to maintain said tubes glowing upon energization of said grids, means at each telephone set connected to a telephone line for applying a potential to said line sufficient to energize the grids of the corresponding tube and cause said tube to glow, means interposed between each line and its corresponding tube for filtering out potentials due to interpair line leakages and pickup of radio frequency signals by said lines.

7. In a local battery telephone system, the combination of at least two telephone lines, a

party telephone set connected to said each of said lines, a switchboard, an electronic glow tube corresponding to each telephone line at said switchboard, each tube having a plate, a cathode and a pair of grids, means connecting each telephone line to the grids of its corresponding tube, means at the switchboard for applying a potential to the plate and cathode of each tube, said potential being insufficient to cause said tubes to glow, but sufficient to maintain said tubes glowing upon energization of the grids thereof, means operable at each telephone set for energizing the grids of its corresponding tube sufficiently to cause said tube to glow, an operator's telephone set at said switchboard, means at said switchboard for supplying a ringing potential to a party telephone set, switching means at said switchboard corresponding to each party telephone set for connecting said operator's set to the corresponding party set and simultaneously removing the potential from the plate and cathode of said corresponding tube, means at said switchboard for connecting a telephone line corresponding to a called party to another telephone line corresponding to a calling party, said switching means further being operable to disconnect said lines and connect said source of ringing potential to the telephone line corresponding to the called party.

8. In a local battery telephone system, the combination of at least two telephone lines, a party telephone set connected to said each of said lines, a switchboard, an electronic glow tube corresponding to each telephone line at said switchboard, each tube having a plate, a cathode and a pair of grids, means connecting each telephone line to the grids of its corresponding tube, means at the switchboard for applying a potential to the plate and cathode of each tube, said potential being insufficient to cause said tubes to glow, but sufficient to maintain said tubes glowing upon energization of the grids thereof, means operable at each telephone set for energizing the grids of its corresponding tube sufficiently to cause said tube to glow, an operator's telephone set at said switchboard, means at said switchboard for supplying a ringing potential to a party telephone set, switching means at said switchboard corresponding to each party telephone set for connecting said operator's set to the corresponding party set and simultaneously removing the potential from the plate and cathode of said corresponding tube, means at said switchboard for connecting a telephone line corresponding to a called party to another telephone line corresponding to a calling party, and simultaneously disconnecting the grids of the tube corresponding to the called party set from its corresponding telephone line, said switching means further being operable to disconnect said lines and connect said source of ringing potential to the telephone line corresponding to the called party.
